United States Patent Office

Des. 191,247
Patented Aug. 29, 1961

191,247

PENCIL POINTER

Arthur C. McWilliams, 333 Barton, Evanston, Ill.

Filed Mar. 16, 1961, Ser. No. 64,343

Term of patent 14 years

(Cl. D74—21)

FIG. 1

FIG. 2

FIG. 3

FIG. 1 is a perspective view of a pencil pointer showing my new design;

FIG. 2 is a front elevational view thereof; and

FIG. 3 is a fragmentary side elevational view thereof.

I claim:

The ornamental design for a pencil pointer, as shown.
